UNITED STATES PATENT OFFICE.

WILLIAM H. McNARY, OF BROOKLYN, NEW YORK.

IMPROVEMENT IN COUNTING-REGISTERS.

Specification forming part of Letters Patent No. 103,221, dated May 17, 1870.

To all whom it may concern:

Be it known that I, WILLIAM H. McNARY, of Brooklyn, in the county of Kings and State of New York, have invented a new and useful Improvement in Counting Apparatus, of which the following is a full, clear, and exact description, reference being had to the accompanying drawing, forming part of this specification, and in which—

Figures 1 and 2 represent central sections, looking in opposite directions, of a counting apparatus constructed in accordance with my invention; and Fig. 3, a view, at right angles to Figs. 1 and 2, of said apparatus, with one of the outer plates of the case removed.

Similar letters of reference indicate corresponding parts.

My improvement is applicable to counting apparatus for various purposes, including the counting of revolutions in machinery, gas or water indicators, adding-machines, and registering devices of different kinds. It may be extended indefinitely as regards the multiplication of its count or range, but it will suffice here to illustrate the action as restricted to the two denominations of units and tens.

The improvement consists in a certain combination of counting-wheels, provided with spur-gear pinions arranged to mesh into the latter, also (or certain of them) into toothed sectors carried by each counting-wheel of the next lower denomination, and locking-stops attached to said pinions, to hold each counting-wheel of a higher denomination from moving till the toothed sector of the next wheel of a lower denomination comes round to operate the pinion, which gives the necessary extent of motion to the adjacent counting-wheel of a higher denomination, when the locking-stop is temporarily relieved by a recess in the counting-wheel of lower denomination coming round opposite it.

Referring to the accompanying drawing, A represents a case or box, which may be of any suitable form, and which has an opening or apertures, a, in one of its sides or edges, for exposure of each number in succession arranged around the peripheries of the counting-wheels B C. These counting-wheels are hung to rotate upon a fixed central shaft or pin, s, extending from side to side of the case.

These wheels carry spur-gear or toothed rings b c on their one side or face, into which mesh independent pinions D and E, the one, D, of which represents the primary operating-pinion, and may be actuated by any suitable power or mechanism it is required to connect the counting apparatus with, and is in gear with the spur-teeth b of the counting-wheel B, that is the unit-wheel of the counter.

The other pinion, E, works loose on a pin, d, and meshes with the spur-gear c of the counting-wheel C, which, moving a number each time the unit-wheel completes a revolution, counts tens, and so on in succession for any number of counting-wheels with pinions, and their operating and locking attachments, as hereinafter described, according to the required range of the counter.

Each pinion E is made sufficiently wide to gear not only with the spur-gear c of its counting-wheel C, but also with a toothed sector, F, attached to the adjacent counting-wheel B of a lower denomination; and, furthermore, each pinion E is provided with a triangular or other suitable stop, G, which, resting on the periphery of the adjacent counting-wheel B of a lower denomination, locks the higher counting-wheel C from being moved till the toothed sector F of the wheel B, and a recess, e, in the periphery of said wheel, come round to relieve the stop G, and to allow of the actuation of the pinion E by said sector, after which, by the continuation of the travel of the wheel B, the stop G is again made to lock the pinion E, and, through it, the wheel C.

Every action thus communicated to the counting-wheel of a higher denomination, each revolution of the adjacent counting-wheel of a lower denomination moves the first-named counting-wheel a number, the sector and pinion it operates having a proper relative number of teeth to secure such certainty of action.

The counting-wheels will, of course, be divided according to the numeration to be made, and will vary with the different purposes to which it is proposed to apply the invention, a different count to that here described being, for instance, required in its application to clocks, or to the calendar-movements of clocks, and, in some cases, it may be desirable to

provide for the adjustment or correction of the counting-wheels, as in the case of the stopping of a clock. This may be done by making the peripheral portions of said wheels on which the numbers are arranged movable circumferentially.

The same system of stops, pinions, gears, and sectors is applicable, with very slight modification, in connection with counting or indicating wheels arranged to indicate by means of figures upon faces parallel with their planes of revolution.

What is here claimed, and desired to be secured by Letters Patent, is—

The combination, with a series of counting-wheels and spur-gear, *c*, connected with each counting-wheel of a higher denomination, of the pinion *E*, stop *G*, and recess *e*, and toothed-sector *F*, provided in and on the wheel of lower denomination, substantially as shown and described.

WM. H. McNARY.
